TERMINAL ARRANGEMENT

John H. Jaidinger, Chicago, Ill.

Application March 25, 1950, Serial No. 151,908

1 Claim. (Cl. 339—217)

This invention relates to a relay construction. More particularly it relates to the provision of a sturdier construction of that portion thereof which carries the terminal lugs, as well as the lugs themselves. By terminal lugs I refer to the means by which the incoming electrical conductors are connected to the relay operating coil.

Conventionally the ends of the coil winding are brought out through apertures in one of the end plates of the bobbin upon which the coil is wound, and by means of a hollow rivet the coil end is held against the end plate, the incoming lead being positioned in the center of the rivet and soldered. In other constructions the rivet secures a terminal lug to which the incoming conductor is soldered. In the first case the handling of the incoming lead and the heat of soldering quite often results in breakage or weakening of the usually fine gauge coil wire, or in loosening of the rivet. In the latter case the lug, which is held at only one end, may become loose with respect to the rivet, or due to careless handling and vibration during use the lug and rivet together with a portion of the end plate may be broken off.

In view of the foregoing, it is one of the objects of the invention to provide a sturdy construction for associating the terminal lug with the coil.

Another object resides in constructing the end plate of the coil of the relay and the mounting frame thereof in their relation to one another so as to result in substantially greater support for those portions of the end plate to which the terminal lugs are secured.

Still a further object is to arrange the assembly of the coil end plate and terminal lugs so as to yield a minimum transverse dimension.

An additional object resides in providing a terminal lug of substantially greater rigidity without increasing the thickness of the sheet stock employed therefor.

Other objects will become apparent as the description proceeds.

In the drawing which shows one form in which the invention may be embodied:

Fig. 1 is a side elevational view of a typical relay embodying the invention;

Fig. 2 is an end view thereof;

Fig. 3 is a cross sectional view taken on the line 3—3 of Fig. 1;

Fig. 4 is a cross-sectional view taken on the line 4—4 of Fig. 1; and

Fig. 5 is a perspective detail of one of the terminal lugs.

While the invention is capable of a wide range

of the invention to provide a sturdy construction to a simple relay in order to provide suitable environment. Broadly the invention is intended for use in any application involving a coil or similar electrical component which is to be placed in circuit with external wiring.

Turning to the drawing, the relay there shown includes a steel frame or yoke 10 which also serves as part of the flux path of the operating coil 11. Frame 10 is substantially of Z-shape and includes a lower horizontal leg 12, a vertical leg 13 and an upper horizontal leg 14. Coil 11 is secured in any convenient manner, as by staking a shouldered end of the core 16 thereof, to leg 12. Leg 14 supports a contact stack or stacks 18 of any form, which form no part of the invention and will not be further described. An armature 19 of any suitable character is adapted, through an insulated extension 21, to operate the contacts of stacks 18, and is hinged, as at 22, with respect to vertical leg 13. A coil spring 23 intermediate the rearward extension of the armature 19 and the frame 10 biases the former to rest position.

Directing attention particularly to the gist of the invention the coil 11 comprises a winding 26, a lower end plate 27 and an upper end plate 28, both latter being of electrically insulating material. Upper plate 28 is preferably of the form shown (Fig. 3), including a semi-circular part, a rectangular part, and a pair of rearwardly extending, preferably rectangular, projections 29—29. These latter are snugly received in slots or notches 31—31 (Fig. 2) in the opposite edges of leg 13, whereby substantial interlocking support is provided for those corners of the plate 28 overhanging the perimeter of the winding 26, and to which are secured the terminal lugs now to be described.

The two leads (not shown) forming the termini of the winding 26 are brought out and soldered to hollow rivets or similar means 35—35, secured to plate 28 beyond the perimeter of the winding. Also secured by rivets 35 is a pair of terminal lugs 36—36 (Fig. 5), each comprising an attaching part or ear 37 and a wire connecting part 38. Aperture 39 receives the shank of rivet 35 or its equivalent and aperture 41 receives the external conductor, which is usually soldered in place.

It will be particularly noted that parts 37 and 38 are mutually perpendicular in order that downward stress imposed on the lug by conductors secured at aperture 41 is absorbed on an edgewise disposed member, and as contrasted

with a conventional terminal lug which is disposed flatwise and thus easily deformed by an external force. Moreover, due to its novel form, the lug of the invention may be made of substantially lighter stock than would be the case for a conventional terminal lug made entirely in one place.

By tightly fitting the projections 29-29 in notches 31-31 any strain on the plate 28 due to the external conductors or other force is received principally by the steel yoke or frame 13 thereby rendering practically negligible any danger of breakage of the frangible insulating material of which plate 28 is usually composed. It will be understood that the notches 31-31 may find their equivalent in closed apertures or surface recesses in the leg 13.

Referring specifically to Fig. 3 it will be seen that plate 28 is recessed on each edge as at 30-30 to receive connecting part 33 of lug 36 in flush relation with the margins of the plate. Thus employment of the lug of the invention need not require a transverse dimension for the assembly greater than that of the plate 28 alone, and the compactness of the assembly is thereby considerably enhanced.

In the embodiment of the invention shown connecting part 33 of a lug 36 is so disposed as to require electrical clearance with respect to the leg 13 of yoke 10. Accordingly notches 45-45 (Fig. 2) may be provided for such purpose. However the depth of such notches should be minimized in order not to reduce unnecessarily the available cross section of the leg 13 which forms part of the electromagnetic circuit. In this connection it is to be noted that by disposing the connecting part 33 of the lug 36 vertically edgewise, the depth of the clearance notch 45 may be reduced substantially over what would be required by the conventional horizontally edgewise positioning of the terminal lug. Obviously a lug positioned in the conventional manner occupies greater space transversely, whereas compactness in that direction is often an important desideratum. My invention is of particular advantage for such applications.

Another important advantage resides in the locking of the terminal lug against rotation about its attaching rivet or equivalent. In one type of prior construction, the lug was so locked by engaging a downwardly bent ear of the lug in an aperture of the end plate of the coil, sometimes described as the "anchor" lug. Such construction was largely ineffective since the plate is weakened by forming the additional hole therein, and upon even moderate rotational force the anchoring ear could twist out of the aperture. Moreover such lug required considerable space beyond the coil perimeter with resultant undesirable overhang of the end plate. Another form of lug designed with a view to resisting rotation was provided with a square integral shank fitted within a square aperture in the end plate. This construction was deficient in that the soldering iron often heated the plastic end plate to the point where play was created between the shank and aperture, likewise with detrimental consequences.

Obviously this last mentioned shortcoming is to be expected with those lugs having only a single fastening through a single hole and no other means to withstand pivotal stress.

5 The lug of the invention is proof against pivotal displacement by having the bent down portion 38 lodged lightly against the edge of the end plate. It is not necessary that the recesses 30-30 be provided in every case. By way of example such recesses are shown, but only to indicate that the transverse dimension of the relay may be minimized by nesting the connecting portion of the lug in a recess. Equivalent structural advantages, i. e., resistance to bending and pivoting, may be obtained without resorting to recesses 30-30.

10 It will be understood that the invention is of particular benefit in those cases where the end plate must be maintained to dimensions only slightly greater than the exterior diameter of the coil, and for considerations of space.

15 While I have shown particular embodiments of my invention, it will be understood, of course, that I do not wish to be limited thereto since many 20 modifications may be made, and I therefore contemplate by the appended claims to cover any such modifications as fall within the true spirit and scope of my invention.

Having thus described my invention, what I 30 claim and desire to secure by Letters Patent is:

A terminal and end plate construction for a bobbin upon which a solenoid is wound comprising a relatively thin plate of electrically-insulating material having a surface and two edges meeting in a corner, one of said edges having an elongated notch opening into the other edge, and a terminal lug including a mutually perpendicular ear and elongated wire-attaching portion, the ear being juxtaposed to said surface and secured thereto, and the wire attaching portion being abutted against the wall of the notch with the exterior face of the portion substantially flush with said one of said edges and projecting beyond said corner.
